UNITED STATES PATENT OFFICE.

CLARENCE C. HUNICKE, OF NEW YORK, N. Y., ASSIGNOR TO PREPAYMENT CAR SALES COMPANY, OF NEW YORK, N. Y., A CORPORATION OF WEST VIRGINIA.

PREPAYMENT-CAR.

1,134,387.

Specification of Letters Patent.

Patented Apr. 6, 1915.

Application filed September 5, 1912. Serial No. 718,623.

To all whom it may concern:

Be it known that I, CLARENCE C. HUNICKE, a citizen of the United States, residing at New York, in the county and State of New York, have made a certain new and useful Invention in Prepayment-Cars, of which the following is a specification.

One object of the invention is to provide a passenger car for street or other railways embodying means which are simple in construction and arrangement, whereby the collection of fares as the passengers enter the car is facilitated.

Another object of the invention is to secure more platform space than is possible with the ordinary prepayment car.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

Referring to the accompanying drawings and to the various views and reference signs appearing thereon: Figure 1 is a broken view in horizontal section of one end of a passenger car showing the application thereof to of features embodying the principles of my invention. Fig. 2 is a similar view showing a modified form of door arrangement that is capable of use in connection with my invention. Fig. 3 is a broken view in vertical section of the door operating mechanism.

The same part is designated by the same reference sign wherever it occurs throughout the several views.

The problem of safely handling the street car traffic while at the same time securing rapid transit, and especially in the larger cities, has become a very serious and difficult one. Many means have been resorted to in order to solve this problem. The method generally adopted and known as the pay-as-you-enter or pay within, or prepayment, type of car, involves the use of various arrangements of railings or other means to divide the platform into entrance and exit passageways, the conductor being stationed so as to collect the fares from the incoming passengers as they enter. In order to con-

vert the cars already in use into fare prepayment type a considerable expense of reconstruction is entailed since room must be provided on the platform for both the doors and the railings or other dividing means. This requires that the car roof and floor be extended to provide for the required increase of platform area, and in some cases the whole car in a large measure must be rebuilt to adapt it for prepayment use.

My invention relates to passenger cars of the class described and it contemplates means whereby the fares of entering passengers are collected as they enter, whereby the use of dividing rails or barriers on the platform is avoided, and whereby the doors themselves, when open, form the necessary passage separating barriers thereby enabling the ordinary cars to be readily and at a slight expense converted into cars of the fare prepayment type.

In carrying out my invention, I propose to arrange the doors so that, when opened, they divide the platform space into separate exit and entrance passageways and form a space between the doors for the conductor so that he can collect fares from the entering passengers.

It is obvious that any suitable type of door operating mechanism and any convenient type of door can be used suitable to the various styles and types of cars.

While, therefore, I have shown and will now describe my invention in a preferred embodiment thereof it is to be understood that I do not desire to be limited or restricted in respect to the specific details shown.

Referring to Figs. 1 and 2, reference sign 1, is the car body; 2 is one of the vestibule ends thereof; 3, wall seats. As shown, the car is provided with a vestibule or platform having the side doors 6, 6', and 7, 7', on opposite sides thereof, any convenient type of platform side steps 8, may be employed.

In the form shown in Fig. 1, the doors 6, 6', are at the entrance side of the platform 100 while the doors 7, 7' are on the opposite or normally closed side of the platform, the end of the car shown being, in the case of the usual prepayment type of car, the rear end, the doors 7, 7', in that case being ordinarily 105 kept closed while the doors 6, 6', are oper-

ated to open and closed positions as occasion requires, to control the entrance and exit of passengers.

The platform space is separated from the interior or seating space of the car by means of doors 26, 27. In the form shown in Fig. 1, these doors are in the form of swinging doors, the door 27 being the entrance door and hinged at the edge upon a vertical axis 5. 10 30 positioned at a point intermediate the transverse width of the car. In opening this door 27, as indicated by dotted lines in Fig. 1, swings out over the platform space and approximately in the direction of the length 15 of the car. The door 26, may be regarded as the exit door and is hinged at one edge upon a vertical axis 31, placed adjacent the side of the car. As shown in dotted lines, in opening, this door swings inwardly. The doors 20 6, 6', are hinged at their adjacent edges upon vertical shafts 32, 33, which are positioned at approximately the midwidth of the platform side opening. As shown in dotted lines in Fig. 1 the doors 6, 6', swing inwardly over 25 and transversely across the platform in opening. The construction and arrangement and method of operation of the doors 7, 7', is not of consequence so far as my present invention is concerned.

30 From the foregoing arrangement it will be seen that by opening the doors 6, 6', and 27, as shown in dotted lines, the said doors assume relative positions over the platform which enable them to form barriers or entrance and exit passage separating means without requiring the employment of any special barrier for that purpose. Of course the presence or absence of the exit door 26 is not of material consequence as far as concerns the function of the doors 6, 6', and 27 40 in forming separate entrance and exit passageways across the platform. When the doors 6, 6' and 27, are closed, the entire area of the platform is available for the accommodation of passengers.

45 In Fig. 2, I have shown the entrance doorway from the platform to the interior of the car, controlled by the doors 27, 27' respectively carried by vertical shafts 30, 34. In this case only the section 27 of the door operates in forming the passage separating means over and across the platform, as shown in full lines in Fig. 2. In the arrangement I have also shown the door 26, 55 as opening outwardly.

When the doors 27, 6 and 6', are opened as above explained, they not only serve to form passage separating barriers across the platform, but they also afford a convenient 60 station for the conductor adjacent the proximate edges of the opened doors which form an inclosure for the conductor, and from which station the conductor collects the fares of passengers as they enter.

65 It may sometimes be desirable to provide

operating devices for the various doors and to control their operation from the fare prepayment station. I have shown an arrangement for accomplishing this result which is simple and efficient, wherein a control stand is located on the platform at a point between the proximate edges of the doors 6, 6', and 27, when said doors are in open position. This control stand includes the shaft 23, having an operating handle 19, and arranged 70 to extend longitudinally through a sleeve 24, the latter having an operating handle 20 at its upper end. This sleeve also passes longitudinally through another sleeve 25, which in turn is also provided with an operating 75 handle 18 at its upper end. The members 23, 24, 25, are respectively connected at their lower ends to devices for controlling or operating the doors 6, 6', and 27. In the form shown the lower edges of the member 23, is 80 connected through crank arm 16, and link 31, to a crank arm 21 on the shaft 30 of the door 27, whereby said door may be normally opened and closed by the conductor at the fare prepayment point. Similarly the sleeve 85 24, is connected by arm 15, link 29, and crank arm 11, to shaft 32 of door 6, while sleeve 25 is connected by crank arm 17, link 30 and crank arm 12, to shaft 33 of door 6'. By this arrangement the various doors may 90 be independently operated or controlled from the fare prepayment station. If desired the exit doors 26, 6', may be coincidentally operated. This result may be accomplished by a link connection 32, between 95 crank arms 13 and 14, on the shafts 33 and 31, respectively, of said doors.

If desired a fare box 28, may be associated with the control stand.

From the foregoing description it will be 105 seen that I provide an exceedingly simple arrangement of fare prepayment car wherein in the entering and leaving passengers are separated into two different streams without providing any auxiliary barrier or passage 110 separating means other than that afforded by the doors themselves, thereby leaving the entire platform space available for the accommodation of passengers. This is a most advantageous feature since passengers may 115 board the car at a crowded corner, for instance, and be accommodated on the platform and the entrance or platform side door closed the car started ahead toward the next street crossing before all the entering passengers have paid their fares and passed on 120 inside the car. This enables rapid transit with closer time schedules to be maintained and expedites the operation of the car.

Having now set forth the object and nature of my invention and various arrangements embodying the principles thereof, what I claim as new and useful and of my own invention, and desire to secure by Letters Patent is:—

1. A car having a platform, an entrance and an exit door separating the platform from the interior of the car, doors for said doorways, said entrance door mounted to swing, in opening, outwardly over the platform to form a barrier to divide the platform into separate entrance and exit passages.

2. A car having a platform, an entrance and an exit doorway separating the platform from the interior of the car, doors for said doorways, said entrance door mounted to swing, in opening, outwardly over the platform to form a barrier to divide the platform into separate entrance and exit passages, and means for operating said entrance door.

3. A car having a loading and unloading platform, a doorway in the side of said platform, an entrance doorway from the platform to the interior of the car, swinging doors for said doorways, said doors, when swung into open position extending across the platform and coöperating to form a barrier to divide the platform area into separate entrance and exit passages.

4. A car having a loading and unloading platform, a doorway in the side of said platform, an entrance doorway from the platform to the interior of the car, swinging doors for said doorways, said doors, when swung into open position extending across the platform at an angle to each other with their free edge adjacent each other, and co-operating to form a barrier to divide the platform area into separate entrance and exit passages, and means located adjacent

the free edges of said doors when in open position for independently controlling the movements of said doors.

5. A car having a platform, an exit door from the car to the platform an exit door from the platform to the street, and means for simultaneously moving said doors to open or closed position.

6. A car having a platform, an entrance and exit door between the platform and the interior of the car and an entrance door at the side of the platform, said entrance doors, when in an open position, extending angularly to each other across the platform and coöperating to form a barrier to divide the platform into separate entrance and exit passages.

7. A car having a loading and unloading platform, a door separating said platform from the seating space of the car, a door controlling the street opening of the platform, said doors mounted, respectively, to swing, in opening, the one outwardly and the other inwardly over or across the platform to bring their free edges into proximity to each other, and, when in open position, forming a barrier to divide the platform area into separate passages.

In testimony whereof I have hereunto set my hand in the presence of the subscribing witnesses, on this 29th day of August A. D. 1912.

CLARENCE C. HUNICKE.
